UNITED STATES PATENT OFFICE.

ROMAN WALDEMAR RITTERS, OF LOS ANGELES, CALIFORNIA.

DESIGN FOR A BADGE OR SIMILAR ARTICLE.

46,292.

Specification for Design.

Patented Aug. 18, 1914.

Application filed September 27, 1913. Serial No. 792,215. Term of patent 3½ years.

To all whom it may concern:

Be it known that I, ROMAN W. RITTERS, a citizen of the United States, residing at Los Angeles, in the county of Los Angeles, State of California, have invented a new, original, and ornamental Design for a Badge or Similar Article, of which the following is a specification, reference being had to the accompanying drawing, forming part thereof.

The figure is face view of the badge or similar article illustrating my new design.

I claim:

The ornamental design for a badge or similar article as shown.

ROMAN WALDEMAR RITTERS.

Witnesses:

MERLE HAMMOND,

MARIE BATTEY.
